Charles F. Franz

UNITED STATES PATENT OFFICE.

CHARLES F. FRANZ, OF RICHLVILLE, MINNESOTA.

COMBINATION SCREEN AND STORM DOOR.

1,242,789.

Specification of Letters Patent.

Patented Oct. 9, 1917.

Application filed November 5, 1914. Serial No. 870,533.

To all whom it may concern:

Be it known that I, CHARLES F. FRANZ, a citizen of the United States, residing at Richville, in the county of Ottertail and State of Minnesota, have invented certain new and useful Improvements in Combination Screen and Storm Doors; and I do hereby declare the following to be a full, clear, and exact description of the invention, such as will enable others skilled in the art to which it appertains to make and use the same.

This invention relates to doors and more particularly to a combined screen and storm door.

The invention has for its primary object to provide a simple and efficient screen door which may be quickly and conveniently converted by the mere insertion of an imperforate panel into an efficient storm door.

Another object is the provision of novel and efficient means for reliably and detachably securing the panel or door covering in position.

With these and other objects in view, the invention consists in the novel construction, arrangement and formation of parts as will hereinafter specifically described, claimed and illustrated in the accompanying drawing, in which:

Figure 1 represents a front elevation of a combined screen and storm door, partly opened away.

Fig. 2 represents a transverse sectional view on the line 2—2 of Fig. 1.

Fig. 3 represents a fragmental longitudinal sectional view taken through the upper portion of the door on the line 3—3, and

Fig. 4 represents a fragmental longitudinal sectional view taken through the lower portion of the door on the line 4—4 of Fig. 1.

Referring to the drawing in detail, where similar reference numerals designate corresponding parts throughout the several views, the numeral 5 indicates the frame of door generally, which is preferably provided with a center vertical mullion 6 and mullion 7. The openings between the mem-

bers of the door frame are covered by a fly screen 8 suitably secured to the door frame.

Vertically and horizontally disposed guides 9 and 10, respectively, are secured adjacent the inner edges of the vertical side and bottom members of the door frame and are preferably U-shaped in cross section, as clearly indicated in Figs. 2 and 4, to permit insertion of the imperforate panel or cover 11. Clamping strips 12 and 13 are secured to the vertical mullion 6 and mullion 7 respectively, by wing nuts and bolts 13^a and firmly clamp the screen 8 and panel or cover 11 against the vertical mullion and mullion 7. A clamping bar or strip 14 is secured to the upper horizontal member of the door frame between the upper extremities of the vertical guides and reliably clamps the upper edge of the panel or covering 11 against the upper portion of the door frame.

The panel or cover 11 may be constructed of wood or any other suitable material, but by preference a sheet of relatively thick water-proof paper such as is commonly used by builders for temporary roofing is used. An aperture 16 constituting a window is formed in the upper portion of the cover or panel 11 and is closed by a transparent insert 17 suitably secured to the inner surface thereof.

During relatively cold weather the door panel or cover 11 is positioned in the guides 9 and 10 and is reliably secured in position on the door frame by the clamping strips 12, 13 and 14 and the wing nuts and bolts 13^a, whereas during the warm summer months the clamping strips 12, 13 and 14 are removed, the panel or cover 11 withdrawn from the guides and the clamping strips are replaced to reliably secure the screen 8 in position upon the door frame.

What I claim is:

A combined screen and storm door comprising a frame having vertical and horizontal mullions, a screen mounted upon the frame, guides located at opposite sides of the frame and extending downwardly from the top thereof and provided with a con-

necting portion extending across the bottom of the frame and closing the lower ends of the guides, a panel or cover extending from the top to the bottom of the frame and 5 slidably arranged within the said guides and introduced into the same at the upper ends thereof and clamping bars extending across the top of the frame and along the said

mullions and detachably securing the said cover or panel in the guides.

November 2nd, 1914.

CHARLES F. FRANZ.

Signed in our presence:

G. F. BROOKS,

C. G. HAYHURST.
